UNITED STATES PATENT OFFICE.

JOHN HILDE AHLGREN, OF NEW YORK, N. Y.

SAFETY GAS-BURNER.

No. 909,508.

Specification of Letters Patent. Patented Jan. 12, 1909.

Application filed July 8, 1908. Serial No. 442,458.

To all whom it may concern:

Be it known that I, JOHN HILDE AHLGREN, a subject of the King of Sweden, residing in the borough of the Bronx, city, county, and 5 State of New York, have invented certain new and useful Improvements in Safety Gas-Burners, of which the following is a specification.

My invention relates to illuminating gas 10 burners, and is designed to automatically effect the shutting off of the gas supply in case the flame is blown out or extinguished in any way other than by closing the gas fixture cock in the usual manner, my object 15 being to obviate all danger that might otherwise result from carelessness, ignorance, wind, or other cause.

The invention consists in a special form 20 of gas burner to be attached in the ordinary way to a gas fixture provided with the usual gas cock, said gas burner being formed with an auxiliary valve which is held open, against the resistance of a spring temporarily by a drop lever when the gas is first lighted, and 25 then normally while the gas flame continues by an expansion device which also releases the drop lever, so that should the flame become extinguished the auxiliary valve will 30 be free to close under the action of the spring as the expansion device cools off and contracts, substantially as hereinafter set forth.

In the accompanying drawings, Figure 1, 35 is an elevation of a gas fixture terminal provided with one of my safety burners; Fig. 2, is a central vertical sectional elevation of my safety burner showing the auxiliary valve opened by the drop lever; Fig. 3, is a like view showing the drop lever released and the valve held open by the expansion 40 device.

A, represents an ordinary terminal of a gas fixture provided with the usual gas cock a.

B is my safety burner the lower end of 45 which is tapped to screw onto the male thread on the end of the gas fixture. My safety burner is formed with a gas passage b, closed at top by the usual burner tip t. Interposed in this passage b, is a valve seat 50 c, in conjunction with which is arranged a valve v, on the inner end of a valve rod v', the outer end of which valve rod v', passes through a guide g, which also constitutes the end of the lateral extension b', of the burner B. Inter-

posed between the inner end of the screw plug g, and the valve v, is a spring s, coiled around the valve rod v', and tending constantly to thrust the valve to its seat c.

On the outer end of the valve rod v', is 60 mounted a cam disk D. This may be accomplished by forming the outer end of the valve stem v', with a male screw thread v², for engagement with a female screw thread formed in the hub of the disk D,—a lock nut 65 n, being used to bear against the disk D. By this or equivalent means the adjustment of the disk D, upon the valve stem v', may be provided for, to attain accuracy of adjustment, compensate for wear &c. 70

The inner side of the disk D is concave and is provided with an inner cam surface d, and an outer or peripheral cam surface d'. In conjunction with the peripheral cam surface d', is arranged a drop lever L, pivotally attached to the burner B, at m, and having a long arm preferably provided with a weight w, to insure the fall of the lever L, when its cam arm l² is released from the cam disk D as hereinafter described,—said 80 weight w, also acting as a handle to the lever. 75

E is an expansion tube seated at its lower extremity in a boss or lateral extension b², on the burner B. Suspended within and 85 from the top of the expansion tube E, is a rod P, the lower end of which projects below the tube E and below the boss b², and is formed with a loop r, or otherwise constructed to connect with a detaining arm X, 90 pivotally attached at x, to the burner B, and projecting therefrom into the concave inner side of the cam disk D, and against the cam surface d.

The expansion tube E is made of a metal 95 of suitable expansibility while the rod R is of a metal of a relatively less degree of expansibility, so that the lengthening of the tube E will result in the raising of the outer end of the detaining arm X, against the 100 cam surface d, of the disk D. The extent of movement of the rod R is but slight, but the connection of the rod with the arm X in close proximity to the fulcrum x, of the latter, augments this movement sufficiently to 105 afford the necessary thrust of the detaining arm X.

The adjustment of the rod R with relation to the expansion tube E may be effected by the use of any desired mechanical expedient, 110

as by supporting it upon a head r' , which is adjustable upon the tube by means of a set screw r'' .

The operation is as follows. When it is desired to use the burner, the gas fixture cock a , is opened and the drop lever raised, bringing the end of its cam arm l^2 , into contact with the peripheral cam surface d , forcing the disk D , outward and removing the valve v , from its seat c , against the resistance of the spring s . In this position the outer end of the cam arm l^2 , rests against the flat portion d , of the disk, so that the pressure of the spring s , prevents the drop lever L , from falling back into its normal position. The gas having been lighted at the tip t , the heat of combustion soon expands the tube E , thereby raising the rod R slightly and causing it to press the free end 15 of the detaining arm X against the cam surface d , on the disk D . The slight upward movement of the free end of the detaining arm X , finally presses the disk free of the cam arm l^2 , of the drop lever L , which latter 20 immediately returns to its normal position,—the detaining arm X continuing to hold the valve v , open so long as the heat of combustion maintains the expansion tube extended. When the gas is turned off at the fixture cock a , or is extinguished by any other cause, the cooling and contracting of the tube E allows the spring s , to close the valve v . Thus in case of the extinguishing 25 of the gas from any cause, my auxiliary valve v , by closing automatically obviates

all danger from the escape of unconsumed gas. It also acts as a check and guard against the accidental opening of the fixture cock a , since both the latter, and my auxiliary valve v , have to be open before the 40 gas can pass to the burner tip t .

What I claim as my invention and desire to secure by Letters Patent is,

1. In a safety gas burner, the combination of a valve, a spring which tends constantly to close said valve, a contact surface on the valve stem, a pivoted drop lever by which the valve may be opened through the medium of said contact surface on the valve stem, a pivoted detaining arm arranged to 45 act against a projection on the valve stem, a rod connected with said detaining arm, and an expansion tube connected with said rod, for the purpose described.

2. In a safety gas burner, the combination 55 of a valve, a spring which tends constantly to close said valve, a cam disk on the outer end of the valve stem, a pivoted drop lever arranged to act against said cam disk, a pivoted detaining arm arranged to act against 60 said cam disk, a rod connected with said detaining arm, an expansion tube connected with said rod, and means for adjusting said rod upon and with relation to said expansion tube, for the purpose described.

JOHN HILDE AHLGREN.
